UNITED STATES PATENT OFFICE

157,353

AIRPLANE

William K. Ebel, Kingsville, Md., Peyton M. Magruder, Washington, D. C., and Maxwell B. Bassett, Middle River, Md., assignors to The Glenn L. Martin Company, Baltimore, Md.

Application October 24, 1947, Serial No. 142,132

Term of patent 14 years

(Cl. D71—1)

To all whom it may concern:

Be it known that we, William K. Ebel, Peyton M. Magruder, and Maxwell B. Bassett, citizens of the United States and residents respectively of Kingsville, county of Baltimore, State of Maryland; Washington, District of Columbia; and Middle River, county of Baltimore, State of Maryland, have invented a new, original, and ornamental Design for an Airplane, of which the following is a specification, reference being had to the accompanying drawings, forming part thereof. This application is a continuation in part of our application Serial No. D. 127,020, filed March 1, 1946, now abandoned.

Figure 1 is a perspective view of an airplane, showing our new design.

Figure 2 is a top plan view thereof.

Figures 3 and 4 are front and side elevational views thereof.

The characteristic features of our design are shown by means of full lines in the drawing.

We claim:

The ornamental design for an airplane, substantially as shown and described.

WILLIAM K. EBEL.

PEYTON M. MAGRUDER.

MAXWELL B. BASSETT.
